DESIGN FOR AN OIL BURNER CASING

Otto H. Neuenfeldt, St. Paul, Minn.

Application May 12, 1933, Serial No. 48,085

Term of patent 7 years

To all whom it may concern:

Be it known that I, OTTO H. NEUENFELDT, a citizen of the United States, residing at 1083 Charles Street, in the city of Saint Paul, county of Ramsey, and State of Minnesota, have invented a new, original, and ornamental Design for an Oil Burner Casing, of which the following is a specification, reference being had to the accompanying drawing, forming part thereof.

I claim:

The ornamental design for an oil burner casing, as shown.

OTTO H. NEUENFELDT.
